PHONOGRAPH

George A. White, Philadelphia, Pa., assignor, by
mesne assignments, to Lloyd H. Smith, New
York, N. Y.

Application May 14, 1931, Serial No. 537,353

19 Claims. (Cl. 274—10)

This invention relates to a phonograph and particularly a phonograph embodying mechanism for automatically changing records.

In my application Serial Number 462,456, filed June 20, 1930, there is described a phonograph of this type which, briefly stated, involves the provision of a turntable upon which a plurality of records are stacked, the turntable rotating about an axis inclined to the vertical, and the records being discharged singly from the stack by gravity alone.

The broad object of the present invention may be stated to involve the provision of an improved mechanism involving the same general mode of operation. This improved mechanism is simpler in both construction and operation, being entirely mechanical and so eliminating certain electrical controls in the prior machine.

One specific object of the invention is the provision of a new means for effecting single discharge of records from the stack.

Other objects of the invention relating particularly to details of construction will become apparent from the following description read in conjunction with the accompanying drawings, in which:

Fig. 1 is a plan view of the improved phonograph mechanism and a suitable cabinet therefor;

Fig. 2 is a vertical section illustrating the relationship of certain parts of the phonograph mechanism to a conventionalized cabinet, the major portion of the mechanism being omitted;

Fig. 3 is a vertical section through the mechanism;

Fig. 4 is a bottom plan view of the mechanism;

Fig. 5 is a vertical section taken on the plane indicated at 5—5 in Fig. 3;

Fig. 6 is a vertical section taken on the plane indicated at 6—6 in Fig. 5;

Fig. 7 is a vertical section taken on the plane indicated at 7—7 in Fig. 4;

Fig. 8 is a vertical section taken on the plane indicated at 8—8 in Fig. 4; and

Figs. 9, 10 and 11 are detailed views illustrating various events in the handling of records by the mechanism.

The phonograph is housed in a suitable cabinet conventionally illustrated at 2. If the phonograph is to form an individual unit this cabinet may be of suitable small size. On the other hand if, as is preferred, the phonograph is to be used in combination with a radio set, then a portion of the radio cabinet, preferably the upper portion, is used to form the phonograph housing.

The cabinet in whatever form it may take is arranged to support the plate 4 which carries the mechanism as a unit, providing a suitable frame for the moving parts, so that the entire mechanism is removable from the cabinet. Adjacent the plate 4, which, as illustrated in Fig. 2, is located at an angle so that the axis of rotation of the phonograph records inclines to the vertical, is a suitable record receiving well 6 preferably lined with soft shock absorbing material 8. This well is arranged to receive the records R as they are discharged from the turntable.

Referring now to Fig. 3, it will be seen that there is provided a turntable 10 on which a plurality of records may be stacked, this turntable 15 having a suitable hub 12 splined on the upright spindle 14, the arrangement being such that the hub may move lengthwise of the spindle but will be constrained to rotate therewith. The spindle 14 is driven through suitable reduction gear 20 16 from the motor 18, which continuously rotates.

The hub 12 is journalled in the non-rotatable sleeve 19 which is provided with a radially extending pin engageable by a lever 20 which is urged in a clockwise direction as viewed in Fig. 3 by a spring 22 so as to normally urge the turntable to its extreme upper position. The sleeve 19 which is suitably fixed against rotation, while being arranged to be capable of vertical movement, has a radially extending pointed projection 24 engageable between serrations 26 on a member carried by a plunger 28 which is slidably mounted in frame members and is urged away from the projection 24 by a spring 30. Further reference will be hereafter made to the actuation and purpose of this plunger.

The empty turntable is adapted to be locked in lowered position against the action of spring 22 for purposes of loading through the medium of 40 a hook member 32 engageable with an annular flange 34 formed on the lower side of the turntable, which hook is carried by a rod 36 slidably in the supporting frame and normally urged inwardly by a spring 38. The rod 36 may be retracted to disengage the member 32 from flange 34 by manual manipulation of its upturned outer end 40 which extends through a slot in the plate 4, as indicated in Fig. 1.

The spindle 14 which, as stated above, is driven 50 by the motor 18 through reduction gearing 16, is provided with a worm 42 through which it drives a wheel secured to a shaft 44 journalled in the frame. This shaft has near its lefthand end, as viewed in Fig. 3, a pin 46 forming one member 55

- of a clutch, a sleeve 48 being provided with a suitable slotted edge for engagement with this pin. This sleeve 48 is provided with a slot engaging a pin 50 carried by a cam shaft 52, the pin and slot connection constraining the shaft 52 to rotate upon rotation of sleeve 48, but permitting movement of the sleeve 48 relative to the shaft 52 either against or with the spring 54 which normally engages the sleeve with the pin 46.
- 10 A lever 56 is pivoted to the frame as indicated in Figs. 3, 4 and 8 being urged in a counterclockwise direction as viewed in Fig. 3 by a spring 58, the inner end of this lever is provided with a lug 60 arranged to cooperate with a cam 62 carried 15 by the sleeve 48 for the purpose hereafter described. The lever is adapted to be rocked against the action of spring 58 at a suitable time in the operation of the machine by a cam 64 carried by the shaft 52.
- 20 The opposite end of the lever provides a portion 66 adapted to be engaged by the lower hook end of a latching lever 68 pivoted at 70 to the frame and at its other end at 72 to a member 74 which is urged upwardly by a spring 76 as viewed in 25 Fig. 8. The member 74 is arranged to engage the squared portion 78 of a rod 80 extending from the tone arm supporting member 82 which is rotatable within a sleeve 83 pivoted on the frame by adjustable pivot points 84. At its upper end the 30 supporting member 82 carries the tone arm 86 which at its free end provides a mounting for the pick-up 88 which is preferably of an electrical type. A counterweight 90 carried by the lower end of the member 82 provides a counterbalance 35 for the weight of the tone arm and pick-up.
- Returning to a consideration of the member 74, this member at its inner portion is provided with serrations 92 on its upper end arranged to be engaged at suitable times by the squared portion 40 78 of the rod 80. The lever 68 is provided with an extension 94 arranged in the path of the rod 80 for a purpose which will be hereafter apparent. A pin 96 limits upward movement of the member 74 under the action of spring 76. It may 45 be pointed out that the pick-up needle is maintained in contact with the record by the preponderance of weight of the pick-up and tone arm over the counterbalancing weight 90 and the tension of spring 76 so that while the pick-up is in 50 contact with the record the member 74 will be moved downwardly away from engagement with the stop pin 96, the position of the parts during the playing of a record being as illustrated in Fig. 8.
- 55 A lever 98 is arranged to engage the member 82 when acted upon by a suitable cam 102 carried by a cam disc 104 secured to the shaft 52, the lever 98 being provided with an adjustable cam engaging screw 100 for the purpose of properly 60 adjusting the action of lever 98 in lifting the tone arm from the record.
- Links 106 and 108 are pivoted to the frame being provided at their lower ends with blocks pivoted thereto through which extends a headed rod 65 110 surrounded by a coil spring 112 which serves to urge the links 106 and 108 to parallel position relative to each other against the heads of the rod 110. The link 106 carries a plate 114 engageable by a pin 116 carried by the disc 104, and 70 adapted upon such engagement to cause the linkage to swing to the positions illustrated in construction lines in Fig. 7 to carry the pick-up outwardly toward the periphery of the records. The spring 112 provides that this movement of the 75 rod 80 be of yielding nature since in case the rod

80 is positively stopped the spring 112 will yieldingly permit the link 106 to take its full motion under the action of spring 116 and permit the link 108 to stop as determined by the ultimate position of the rod 80.

Upright standards 118 support a pin 119 in their upper ends on which pin is pivoted a lever 120 urged by a spring 122 to bring an adjustable cam follower 124 carried thereby into engagement with a cam 126 carried on the disc 104. At its upper end the lever 120 carries a spring pressed latch 128 engageable within a slot in a retaining arm 130 to normally maintain said arm in its lowered position. By manipulation of the latch 128 against the action of its operating spring the 15 arm 130 may be released and raised to an angle such as that illustrated in Fig. 3. The arm 130 normally extends to a position overlying the end of spindle 14 so as to carry a rotatable retaining plate 132 into axial alignment with and either 20 enveloping or substantially against the end of said pin so as to engage the topmost record of a stack on the turntable. The plate 132 is suitably journalled in the arm 130 by the use of antifriction bearings so that no substantial resistance to 25 turning of the turntable is offered thereby. Preferably the pin extends a short distance above the topmost record during playing, being received in an opening in the plate 132.

Journalled in the frame at 136 is a lever 134 urged by a spring 138 to bring its lower end into contact with the acting edge of a cam 140 carried by the shaft 52. To the upper end of the lever 134 is pivoted a sleeve 142 which rests upon an eccentric stop 144, this eccentric stop being rotatable through manipulation of its supporting spindle 145 to either the illustrated position wherein the sleeve 142 locates to the parts it carries to discharge a record, or to a position wherein the sleeve is raised to prevent such discharge, the 40 limiting positions being defined by engagement of a pin 147 on spindle 145 with suitable stops. Slidable within the sleeve 142 is the rod 146 urged outwardly by a spring 148 acting against a pin 150 carried by the rod to a position wherein the 45 head 154 on the outer end of the rod engages the sleeve thereby limiting its inward movement. The inner end of the rod carries a wedge shaped member 156 to which is pivoted at 157 a feeler 158 urged in a clockwise direction, as viewed in 50 Fig. 9 by a spring 160, set into a bore in the finger 158 and reacting against the upper extension of the member 156, this spring serving to urge the feeler member 158 towards the point at the end of the member 156. A bayonet slot 152 in the 55 sleeve 142 receives the pin 150 so that the rod 146 may be held outwardly against the tension of spring 148 in position to cooperate with large records.

A cam 162 carried by the disc 104 is arranged 60 to act upon the plunger 28 which has been herefore described.

An inwardly reciprocating plunger 164 provided with a head extending to an accessible position outside the cabinet and normally urged outwardly by a spring 166 may be forced against the action of this spring into engagement with the member 74, as illustrated in Figs. 4 and 8.

A vertically movable plunger 168 is slidable through a supporting sleeve 169 which provides 70 such friction with the member 168 that it will retain the position in which it is located by manual manipulation of its head 170. In its lowermost position, illustrated in Fig. 8, it is in the path of movement of the rod 80 so that it limits 75

the movement of the rod and therefore the tone arm outwardly. This provides for the suitable location of the pick-up to engage the beginning of the groove of a record of a small, say 10 inch, size. On the other hand, if the plunger 168 is lifted, the rod 80 may move therebeneath whereby the pickup will move further outwardly so as to be in position to engage the outer portion of the groove of a larger, say 12-inch, record.

10 Assuming the table 10 to be empty and the machine stopped in its normal condition, the table 10 will be depressed until hook 32 engages flange 34 to hold it in lowered position. Thereupon, the tone arm will be raised about its pivotal connection with member 82 and arm 130 will also be raised after release of latch 128. The space above the table is thereby cleared and records may be stacked on spindle 14. Following this, the arm 130 is lowered carrying plate 132 adjacent the upper end of spindle 14, and is latched in this lowered position by 128, the lever 120 being now acted upon by cam 126. By retraction of hook 32, the table is released so that the topmost record is carried upwardly into engagement with plate 132.

15 The motor may now be started by closure of a suitable controlling switch, and the pick-up needle is lowered into engagement within the groove of the upper record. Playing of the record then 20 takes place.

25 During the playing of the record, the various elements of the record changing mechanism occupy certain normal positions. The member 74 and hook 68 occupy the positions illustrated in Fig. 8, the latter holding lever 56 against the tension of spring 58 so that lug 60, now engaging cam 62, holds the clutch disengaged with the result that shaft 52 is stationary. Cam 64 occupies the position illustrated in Fig. 8 with its high 30 part clearing lever 56. Plunger 28 is disengaged from cam 162 so that the table is free to press the topmost record against the lowered plate 132 under the action of spring 22. Lever 134 engages a low part of cam 140 so that the discharging 35 member 156 is retracted. If record change is to take place, the eccentric 144 is located so that member 156 occupies its lowered position. If small size records are being played, plunger 168 is lowered.

40 Records in common use at the present time are made in two alternative forms for the purpose of actuating usual types of automatic stopping devices, and use is made of the stopping features of these records to operate the record changing mechanism at the end of the playing of the records. In one form of record, there is provided at the end of the sound groove an eccentric circular or oval continuation which oscillates the tone arm. In the other form, the normal spiral at its inner end has an abnormal advance 45 so as to suddenly carry the tone arm a considerable distance inwardly towards the axis of rotation and always a given distance from the center of the record.

50 In the case of the first type of record, as the tone arm moves inwardly during the playing, the arm 80 moves therewith so that its squared portion 78 moves to the right over the serrations 92 which are quite small so that little resistance is offered to movement of the pick-up. This movement to the right only tends to cause the hook 68 to more firmly engage the end 66 of lever 56. However as soon as the eccentric groove is 55 reached, oscillation of the tone arm produces a

reverse movement of member 74 thereby causing hook 68 to disengage lever 56.

On the other hand, if a record of the second type is being played, the inward movement of the tone arm causes rod 80 to engage the extension 94 thereby disengaging the hook from lever 56.

60 In either case, the disengagement of lever 56 permits it to rock under the action of spring 58, whereupon lug 60 frees cam 62, effecting engagement of the clutch initiating rotation of shaft 52. Shaft 52 then starts its single revolution to effect the cycle of operation for the discharge of the topmost record and the beginning of playing of the next in order.

65 The first event of the cycle is the movement of plunger 28 to engage the serrated edge of member 26 with point 24 whereby the turntable is locked against upward movement, although continuously rotating. Immediately following this, the clamping plate 132 rises due to the drop of follower 124 from cam 126, the rise of the clamping plate, as shown in Figs. 9 to 11, being sufficient to clear the record during its discharge. Before or during these events, lever 98 is acted 70 upon by cam 102 to raise the pick-up from the record.

75 Following this, cam 140 moves the sleeve 142 inwardly. As this occurs, the finger 158 moves over the edge of the topmost record and, by reason of the spring 160, pulls up with it the wedge 156, the point of which passes between the topmost and second record. It may be pointed out that the finger and point are adjusted to approximately receive a record between them, the rounded outer periphery of the record permitting the point to enter between the two records. Further inward movement causes the wedge 156 to ride up the edge of the second record thereby lifting the topmost one over the spindle 14 as 80 shown in Fig. 10, discharge then taking place due to the action of gravity and the additional effect of rotation, the latter serving to insure discharge of badly warped records or ones which may have become sticky for any reason.

85 As soon as discharge is thus effected, the wedge withdraws, plate 132 is lowered to its normal position, and plunger 28 is disengaged by cam 162, thereby releasing the turntable for rise under the action of spring 22 to bring the next record 90 into contact with the plate 132.

95 During this period, the tone arm, maintained raised by lever 98 is carried outwardly by the action of lever 108 under the operation of pin 116 on member 114, the outward movement being 100 limited by the engagement of plunger 168 by rod 80. In the case of small size records, spring 112 yields to permit this restraint upon movement of lever 108, the normal movement of which is, of course, such as to carry the pick-up to the beginning of the groove of a large record. As the outer limit of movement is reached, the cam 102 releases lever 98 permitting the pick-up needle to engage the record. As soon as the needle engages the groove playing is resumed.

105 There now remain to be accomplished only those events resulting in stopping of shaft 52 in its initial position. The member 74 turns about rod 80 as fulcrum under the action of spring 16, rocking the hook 68 clockwise as viewed in Fig. 8. 110 Accordingly, when the lever 56 is rocked by cam 64, it will be engaged by the hook and maintained in position so that its lug 60 moves into the path of cam 62 on the clutch member 48. The cam rides over the lug, causing the clutch member to 115

move inwardly and be thereby disengaged with the result that shaft 52 stops. The shaft stops, of course, only after cam 64 moves to a position releasing lever 56 so that it is free to drop upon 5 subsequent tripping.

If instead of a small record, a large size record was played, it would be necessary only to raise plunger 168, so that rod 80 could move thereunder to allow the pick-up its full outward movement, 10 and to adjust the rod 146, carrying the wedge and finger, to its alternate outer position.

If it is desired that any record shall be repeated, eccentric 144 may be turned so that the wedge 156 will ride over the topmost record which will therefore not be discharged. The ordinary cycle will be, however, effected so that the pick-up is returned to the beginning of the record.

If during the playing of a record it is desired to immediately eject it, the plunger 164 may be 20 forced inwardly to trip the hook 68 from lever 56 thereby starting the discharge. It is to be observed that the pick-up may be raised by the mechanism irrespective of its position and will be properly returned to the beginning of the next 25 record.

It is desirable for several reasons that the last record should not be ejected. First, while the machine may obviously be made to stop after playing the last record by the automatic opening 30 of the motor switch, it is preferable to arrange the device so that the motor will run continuously until manually stopped. Under these conditions, repetition of the last record gives warning that the machine is operating and should 35 be stopped. Second, and more important, the needle should not be permitted to ride either on the edge or top of the table, and a record should be in position to receive it.

To attain this result, the table 10 is made 40 smaller in radius than the small size records. As will be obvious from Fig. 11, the result of this is that there is no backing for wedge 156 which accordingly will not rise to remove the record from the spindle. The playing of the last record 45 will therefore be repeated until the machine is stopped.

It will be obvious that numerous changes may be made in the embodiment of the invention without departing from the spirit thereof, as defined in the following claims. For example, while the table is preferably inclined to the vertical to produce gravity discharge in a definite direction, a horizontal table might be provided, the discharge being centrifugal in character.

55 What I claim and desire to protect by Letters Patent is:

1. A phonograph including a pin arranged at an angle to the vertical with its free end uppermost, a turntable for supporting a plurality of records arranged in a stack for rotation about the axis of the pin, means yieldingly urging the turntable towards the free end of the pin, a member engaging the topmost record and cooperating with the turntable to clamp the stack of records, means for holding the turntable from upward movement, means for raising the member while the turntable is so held to release the topmost record for movement from the stack, and means for lifting the topmost record relatively 60 to the next record to clear the pin.

2. A phonograph including a pin arranged with its free end uppermost, a turntable for supporting a plurality of records, arranged in a stack for rotation about the axis of the pin, means yieldingly urging the turntable towards the free end 70

of the pin, a member engaging the topmost record and cooperating with the turntable to clamp the stack of records, means for holding the turntable from upward movement, means for raising the member while the turntable is so held to release the topmost record for movement from the stack, and means for lifting the topmost record relatively to the next record to clear the pin. 5

3. A phonograph including a pin arranged at an angle to the vertical with its free end uppermost, a turntable for supporting a plurality of records arranged in a stack for rotation about the axis of the pin, means yieldingly urging the turntable towards the free end of the pin, a member engaging the topmost record and cooperating with the turntable to clamp the stack of records, means for holding the turntable from upward movement, means for raising the member while the turntable is so held to release the topmost record for movement from the stack, and means for lifting the topmost record relatively to the next record to clear the pin, said last named means including a member reacting between the two uppermost records. 10 15 20 25

4. A phonograph including a pin arranged with its free end uppermost, a turntable for supporting a plurality of records arranged in a stack for rotation about the axis of the pin, means yieldingly urging the turntable towards the free end of the pin, a member engaging the topmost record and cooperating with the turntable to clamp the stack of records, means for holding the turntable from upward movement, means for raising the member while the turntable is so held to release the topmost record for movement from the stack, and means for lifting the topmost record relatively to the next record to clear the pin, said last named means including a member reacting between the two uppermost records. 30 35 40

5. A phonograph including a pin arranged at an angle to the vertical with its free end uppermost, a turntable for supporting a plurality of records arranged in a stack for rotation about the axis of the pin, means yieldingly urging the turntable towards the free end of the pin, a member engaging the topmost record and cooperating with the turntable to clamp the stack of records, means for holding the turntable from upward movement, means for raising the member while the turntable is so held to release the topmost record for movement from the stack, and means for lifting the topmost record relatively to the next record to clear the pin, said last named means including a member engaging the edge of the topmost record. 45 50 55

6. A phonograph including a pin arranged with its free end uppermost, a turntable for supporting a plurality of records, arranged in a stack for rotation about the axis of the pin, means yieldingly urging the turntable towards the free end of the pin, a member engaging the topmost record and cooperating with the turntable to clamp the stack of records, means for holding the turntable from upward movement, means for raising the member while the turntable is so held to release the topmost record for movement from the stack, and means for lifting the topmost record relatively to the next record to clear the pin, said last named means including a member engaging the edge of the topmost record. 60 65 70 75

7. A phonograph including a pin arranged at an angle to the vertical with its free end uppermost, a turntable for supporting a plu- 75

rality of records arranged in a stack for rotation about the axis of the pin, means yieldingly urging the turntable towards the free end of the pin, a member engaging the topmost record and cooperating with the turntable to clamp the stack of records, means for holding the turntable from upward movement, means for raising the member while the turntable is so held to release the topmost record for movement from the stack, and means for lifting the topmost record relatively to the next record to clear the pin, said last named means including a member reacting between the two uppermost records, and a feeler member engageable with the top of the topmost record for guiding said reacting member between the records.

8. A phonograph including a pin arranged with its free end uppermost, a turntable for supporting a plurality of records, arranged in a stack for rotation about the axis of the pin, means yieldingly urging the turntable towards the free end of the pin, a member engaging the topmost record and cooperating with the turntable to clamp the stack of records, means for holding the turntable from upward movement, means for raising the member while the turntable is so held to release the topmost record for movement from the stack, and means for lifting the topmost record relatively to the next record to clear the pin, said last named means including a member reacting between the two uppermost records, and a feeler member engageable with the top of the topmost record for guiding said reacting member between the records.

9. A phonograph including a pin arranged with its free end uppermost, a turntable for supporting a plurality of records arranged in a stack for rotation about the axis of the pin, and means for raising the topmost record relatively to the next record to clear the pin, said last named means including a member reacting between the two uppermost records, the lower of these two records acting as a cam to raise said member.

10. A phonograph including a pin arranged at an angle to the vertical with its free end uppermost, a turntable for supporting a plurality of records arranged in a stack for rotation about the axis of the pin, and means for raising the topmost record relatively to the next record to clear the pin, said last named means including a member reacting between the two uppermost records, the lower of these two records acting as a cam to raise said member.

11. A phonograph including a pin arranged with its free end uppermost, a turntable for supporting a plurality of records arranged in a stack for rotation about the axis of the pin, and means for raising the topmost record relatively to the next record to clear the pin, said last named means including a member reacting between the two uppermost records, the lower of these two records acting as a cam to raise said member, and a feeler member engageable with the top of the topmost record for guiding said reacting member between the records.

12. A phonograph including a pin arranged at an angle to the vertical with its free end uppermost, a turntable for supporting a plurality of records arranged in a stack for rotation about the axis of the pin, and means for raising the topmost record relatively to the next record to clear the pin, said last named means including a member reacting between the two uppermost records, the lower of these two records acting as a cam to raise said member, and a feeler mem-

ber engageable with the top of the topmost record for guiding said reacting member between the records.

13. A phonograph including a pin arranged with its free end uppermost, a turntable for supporting a plurality of records arranged in a stack for rotation about the axis of the pin, and means for raising the topmost record relatively to the next record to clear the pin, said last named means including a member reacting between the two uppermost records, the lower of these two records acting as a cam to raise said member, said turntable being of less diameter than the records whereby the reacting member will be inoperative to effect removal of the last record on the turntable.

14. A phonograph including a pin arranged with its free end uppermost, a turntable for supporting a plurality of records arranged in a stack for rotation about the axis of the pin, and means for raising the topmost record relatively to the next record to clear the pin, said last named means including a member reacting between the two uppermost records, the lower of these two records acting as a cam to raise said member, said reacting member being arranged to take care of records of different sizes.

15. A phonograph including a pin arranged with its free end uppermost, a turntable for supporting a plurality of records arranged in a stack for rotation about the axis of the pin, and means for raising the topmost record relatively to the next record to clear the pin, said last named means including a member reacting between the two uppermost records, the lower of these two records acting as a cam to raise said member, and having alternative paths of movement, in one of which it is operative, and in the other of which it is inoperative.

16. A phonograph including a pin arranged with its free end uppermost, a turntable for supporting a plurality of records arranged in a stack for rotation about the axis of the pin, and means for raising the topmost record relatively to the next record to clear the pin, said last named means including a member reacting between the two uppermost records, and a feeler member engageable with the top of the topmost record for guiding said reacting member between the records, said reacting member and feeler being arranged to take care of records of different sizes.

17. In an automatic phonograph, the combination with a turntable adapted to receive a stack of records, and a reproducer, of means for removing the uppermost record from the stack upon completion of the reproduction thereof including a member normally free of the records, means mounting said member adjacent the turntable for movement substantially in a fixed plane toward and from the records, a single cam operable upon completion of the record for moving said member toward the records and between the uppermost records of the stack, and means for elevating said member upon the continued movement thereof for raising said uppermost record to permit the discharge thereof.

18. In an automatic phonograph, the combination with a turntable adapted to receive a stack of records, and a reproducer, of means for removing the uppermost record from the stack upon completion of the reproduction thereof including a member, means mounting said member adjacent the turntable for movement substantially in a fixed plane toward and from the records, means actuated upon completion of the

record for moving said member toward the records, in a direction substantially parallel to the plane of the turntable, and into engagement with the lower side of the uppermost record of the stack, and means for elevating said member upon the continued movement thereof for raising said uppermost record to permit the discharge thereof.

19. In an automatic phonograph, the combination with a turntable adapted to receive a stack of records, and a reproducer, of means for removing the uppermost record from the stack upon completion of the reproduction thereof including a feeler member having a cam surface thereon, and an associated penetrating member guided

by the feeler member mounted adjacent the turntable for movement toward and from the records, means actuated upon completion of the record for moving said members toward the records and the cam surface of the feeler member into engagement with the edge of the uppermost record of the stack to be cammed upward by said edge to cause the penetrating member to rise and penetrate between the uppermost and next record of the stack, and means for elevating said penetrating member upon the continued movement thereof for raising said uppermost record to permit the discharge thereof. 5 10
